UNITED STATES PATENT OFFICE.

HENRY E. LEPPERT, OF NEW BRITAIN, CONNECTICUT, ASSIGNOR TO THE TRUMBULL ELECTRIC MFG. COMPANY, OF NEW BRITAIN, CONNECTICUT, A CORPORATION OF CONNECTICUT.

ELECTRIC-SWITCH TERMINAL.

Application filed May 31, 1921. Serial No. 473,696.

To all whom it may concern:

Be it known that I, HENRY E. LEPPERT, a citizen of the United States of America, residing at New Britain, Connecticut, have 5 invented a new and useful Electric-Switch Terminal, of which the following is a specification.

My invention relates particularly to the binding post or terminal construction. The 10 main object is to provide a construction which may be readily wired and yet which will hold the end of the wire securely.

Another object is to provide a construction which will facilitate the severing or 15 breaking off of the end of the wire in the operation of wiring.

Another object is to provide a terminal having no projecting lugs or wire retaining means.

20 In its preferred form the invention contemplates the use of what is commonly called a flat terminal for a switch.

Fig. 1 is a side view of a snap switch embodying the improvements of my invention 25 and showing the cover in section.

Fig. 2 is a fragmentary plan view of the switch base and terminal on a larger scale.

Fig. 3 is a sectional view on a plane of the line 3—3 of Fig. 2.

30 Fig. 4 is a perspective view of one of the terminal improvements.

The switch mechanism may be of any suitable type, such for instance, as that shown in the Platt Patent #1,054,939. The base 35 5 supports a spindle 6 which carries the rotary contact member 7.

Each terminal member is conveniently formed of sheet metal, preferably with two lugs 8 and 9 threaded to receive the attaching screws 10 and 11 respectively. The blade portion 12 projects into the path of movement of the rotatable switch blade 7. The terminal plate is notched at 13 to allow for the passage of the wire 14. A portion of 40 45 the plate is depressed or grooved at 15 around the screw seat 16 so as to accommodate the wire beneath the head of the screw 17. The wall of this groove thus forms in effect a lug to prevent the wire from escaping from beneath the head of the binding screw as shown in Fig. 3. To facilitate the breaking off or severing of the end of the wire adjacent the head of the binding screw,

I preferably provide a notch 18 at one edge, as shown in Fig. 4.

To wire the terminal, the insulation is stripped from the end of the wire which is then passed through the base and the stripped end 14 is twisted partway around in the channel beneath the head of the screw 17 and then clamped in place by the screw. The stripped end of the wire ordinarily will be long enough so that a portion will project beyond the screw. This extended portion (not shown) can be readily bent back 65 and forth in the notch 18 a few times until the wire breaks off short at the edge of the notch adjacent the head of the binding screw. This leaves a neat and finished job with no protruding wire and yet with the 70 wire held securely in place.

One great advantage of wiring the switch in this simple manner is that the wire breaks off close to the edge of the plate and thus insures that there will be no projecting wire- 75 ends to prevent the cover from seating properly on the shoulder on the base member.

It is obvious that this terminal is cheaper to make than one having the usual projecting lugs or ears for securing the wire, and 80 it is also obvious that the omission of such ears or lugs is an advantage because of the limited space.

I claim:

1. A switch terminal comprising a plate 85 having anchorage lugs in one plane, a binding screw seat in a plane slightly offset therefrom providing circumferentially extending wire retaining shoulders and a binding screw in said seat with its axis substantially 90 at right angles to the plane of said lugs said shoulders being located around the periphery of the head of said screw, said plate having a wire breaking notch in its edge adjacent the edge of the head of said screw. 95

2. A switch terminal comprising a plate having anchorage lugs in one plane, a binding screw seat in a plane slightly offset therefrom, a binding screw in said seat with its head in a plane substantially parallel to 100 said lugs, and said plate having a wire breaking notch adjacent the edge of said seat and said binding screw.

3. An electrical terminal comprising a plate having a wire-retaining recess off-set 105 from the plane thereof and parallel there-

- with, a binding screw having a head adapted to seat within said recess, said plate having a wire breaking notch adjacent to said recess.
5. An electric terminal comprising a sheet metal plate and a binding screw seated therein, the said plate having a wire break-
- ing notch located in the edge thereof and a shoulder adjacent to the periphery of the head of said binding screw in position to permit a wire to be wound around beneath the head of the screw and bent over and broken off in said notch.

HENRY E. LEPPERT.
